UNITED STATES PATENT OFFICE.

ANTONI PASZKIEWICZ, OF CHICAGO, ILLINOIS.

POLISHING-CYLINDER.

1,162,098.

Specification of Letters Patent. Patented Nov. 30, 1915.

Application filed September 1, 1915. Serial No. 48,535.

To all whom it may concern:

Be it known that I, ANTONI PASZKIEWICZ, subject of the Emperor of Austria-Hungary, residing at Chicago, in the county of Cook and State of Illinois, have invented 5 certain new and useful Improvements in Polishing-Cylinders, of which the following is a specification.

This invention relates to certain new and 10 useful improvements in polishing cylinders.

The primary object of the invention is to provide a polishing cylinder in which emery cloth, sand paper or similar material may be mounted thereon with the meeting edges 15 of the material overlapped and locked within the periphery of the cylinder at the side thereof.

A further object of the invention is to provide a polishing cylinder with a removable 20 covering material that is held in position on the cylinder by fastening means positioned within the periphery thereof, the particular form of fastening means forming the subject-matter of the present invention.

With these general objects in view and others that will appear as the nature of the invention is better understood, the same consists in the novel combination and arrangement of parts hereinafter more fully described, illustrated in the accompanying drawings, and pointed out in the appended 30 claim.

In the drawings forming a part of this application and in which like-designating 35 characters refer to corresponding parts throughout the several views, Figures 1 and 2 are end elevational views, partly in section, and taken on line I—I and II—II respectively of Fig. 3 showing the manner of 40 holding the emery paper upon the cylinder. Fig. 3 is a top plan view of the device partly in section better to illustrate the paper-retaining devices. Figs. 4 and 5 are detail 45 perspective views respectively of the two locking bars.

Referring more in detail to the accompanying drawings, the reference numeral 10 designates a cylinder that may be formed of any suitable material and having a central 50 longitudinal bore 11 to facilitate the mounting of the same and supporting a driven mandrel.

The peripheral face of the cylinder is provided with a fabric covering 12 to prevent 55 slipping movement of the emery paper mounted thereon. While the polishing ma-

terial herein mentioned is referred to as emery paper, it is to be understood that any preferred form of polishing material may be utilized as the occasion may require. 60

A longitudinal slot 13 extends along the periphery of the cylinder 10 and within which slot the meeting edges of the emery paper 14 are adapted to be received. The locking device for retaining the overlapped 65 ends of the emery paper within the groove is clearly shown in Figs. 4 and 5, the same including a pair of bars 15 and 16, the bar 15 being rectangular in cross section, while the bar 16 is substantially semi-circular in 70 cross-section. The overlapped edges of the emery paper 14 are positioned between the lower locking bar 16 and the upper locking bar 15 and clamped in this position by the fastening screws 17 passing through openings 18 in the said bars.

Means are provided for drawing the locking bars toward the inner end of the slot so that the emery paper upon the cylinder 10 will be in close contact with the fabric 12 80 and consists in providing a slot 19 at each end of the cylinder with openings at the ends of the cylinder and positioned slightly below the groove 13. A nut 20 is positioned in each of the grooves 19 and is prevented from 85 turning relative to the cylinder by the side edges thereof contacting side walls of the slot, a threaded opening being provided in each nut 20 through which extends the screw 21, the lower end of which is received in the 90 radial opening 22. By tightening the screw 21 that passes through the end openings 18 in the locking bars 15 and 16, the said screw is adapted to pass through the nut 20 and draw the locking bars 15 and 16 into the 95 slot 13, so that the same may be positioned completely within the periphery of the cylinder 10.

While I have shown and described the preferred embodiment of my present invention, 100 I do not wish to confine myself to the same, but minor changes may be made therein without departing from the spirit and scope of the invention as set forth in the claim.

What I claim as new is:—

A polishing device including a solid cylinder having a central longitudinal bore, there being a longitudinal slot on the periphery of said cylinder, a fabric covering for the cylinder terminating at the edges of 110 the slot, an abrasive material in the form of a sheet positioned on said fabric cover-

ing with the overlapped edges thereof extending into said slot, a pair of locking bars positioned in said slot between which the overlapped edges of the polishing sheet are 5 adapted to be positioned, means for moving the bars toward each other to lock the sheet therebetween, said cylinder having a pair of slots opening at the ends thereof and located directly beneath the aforesaid slot, a nut 10 having its sides engaging the side walls of the slot positioned in each of said slots at the inner ends thereof with the top and bot-

tom faces of the nut engaging the top and bottom faces of the last-named slots, and a locking screw passing through said bars and 15 nuts to draw the locking bars into the lower end of the groove, there being provided a guide opening for the reception of the extended ends of the screws to facilitate a thorough tightening of the abrasive sheet 20 upon the cylinder.

In testimony whereof I affix my signature.

ANTONI PASZKIEWICZ.
